UNITED STATES PATENT OFFICE.

CHRISTIAN S. LEHMAN, OF LAWN, PENNSYLVANIA.

LIFTING-JACK.

1,140,907.

Specification of Letters Patent. Patented May 25, 1915.

Application filed June 8, 1914. Serial No. 843,836.

To all whom it may concern:

Be it known that I, CHRISTIAN S. LEHMAN, a citizen of the United States, residing at Lawn, in the county of Lebanon and State of Pennsylvania, have invented certain new and useful Improvements in Lifting-Jacks; of which the following is a specification.

This invention comprehends certain new and useful improvements in lifting jacks, and has for its primary object to provide a device of this character which will be constructed in such manner that the lifting lever may be readily locked in adjusted position longitudinally of the standard in such manner that the locking means will serve as a pivot for the lifting lever and prevent the lifting lever from moving longitudinally upon the standard while being applied to lift the device with which it is engaged.

Another object of the invention is to provide a lifting device which will be constructed in such manner that the lifting lever may be adjusted longitudinally of the standard and secured in adjusted position in such manner that movement of the lifting lever in one direction will serve to clamp the same upon the standard and make it impossible for the weight upon the forward end of the lever to force the latter downwardly.

This invention has for a further object to generally improve and simplify the construction and operation of the various parts of a device of this character and increase the efficiency thereof without materially increasing the cost of the same.

With these and other objects in view as will become apparent as the description proceeds, the invention consists in certain novel features of construction, combination and arrangement of parts as will be hereinafter more fully described and claimed.

For a complete understanding of my invention, reference is to be had to the following description and accompanying drawings, in which:

Figure 1 is a side elevation of my improved form of lifting lever. Fig. 2 is a front elevation thereof. Fig. 3 is a top plan view. Fig. 4 is a transverse section on the plane of line 4-4 of Fig. 1. Fig. 5 is a vertical sectional view on the plane of line 5-5 of Fig. 2, looking in the direction indicated by the arrows.

Referring more particularly to the draw-

ings by numerals, 1 designates the base from which the divided standard 2 projects upwardly, the end of said divided standard being closed by the cross plate 3 connecting the parallel members forming said divided standard.

The divided standard 2 has a plurality of notches 4 formed in its rear edge and arranged longitudinally of the same for engagement by the central portion of the U shaped lifting lever support 5 mounted in a suitable bracket 6 secured to the lower face of the lifting lever 7 which projects through the divided standard 2. The free ends of the forwardly directed arms of the U shaped lever support are bent upon themselves, as shown at 6, for engagement with the flat face of the standard 2 and are then looped to form the eyes 9 within which are engaged the forward free ends of the spring member 10 which has its central portion twisted to form the eye 11 engaged with the head of the screw 12 or other suitable member secured to the upper face of the lifting lever 7 rearwardly of the standard 2, whereby upon pivotal movement of the lifting lever 7 to force the rear end downwardly and the forward end upwardly, the forward ends of the lever support 5 will be drawn upwardly and forwardly, thereby retaining the central portion of said member 5 in the proper notch 4 and forcing the bent ends 8 of said member 5 against the forward face of the standard 2, making it impossible for the member 5 to be disengaged from the notch 4 to permit downward movement of the lifting lever 7 upon the standard 2.

After the forward or working end 13 of the lifting lever 7 has been engaged with the wagon or other device which it is desired to lift or raise from the ground and the lever operated as above stated, said lifting lever 7 will automatically lock in operated position to retain the object in raised position and absolutely prevent movement of the lever 7 in either direction, by means of the locking bar 14 which has its upper end secured in the eye 15 depending from the rear end of said lever 7, while the main portion of said locking bar 14 is provided in its lower face with a series of forwardly and upwardly directed notches 16 to receive the main portion of the locking rod 17 extending transversely of the lower portion of the standard 2 and having its opposite ends 18 clamped around the lower portions of the

parallel members forming the divided standard 2 to clamp said locking rod 7 in proper position, and it will be evident that during the pivotal movement of the lifting lever 7, 5 to force the forward end 13 thereof upwardly, the notches 16 ride over the locking rod 17. As soon as the pivotal movement of the lifting lever 7 in this direction is discontinued, however, the weight of the object 10 upon the forward or lifting end 13 thereof will force said lever 7 to move in the opposite direction until the adjacent notch 16 comes opposite the locking rod 17, when said locking rod 17 will automatically catch in 15 said notch 16 and lock the lifting lever 7 against further movement in this direction and as it will be evident that the movement of the lifting lever 7 in this direction will be limited and slight, the member 5 will be retained in the proper notch 4 in the standard 2 and thereby will prevent the lifting lever 7 from sliding downwardly upon the standard 2. By disengaging the locking bar 14 20 from the locking rod 17, however, the rear end of the lifting lever 7 may be readily drawn upwardly and the lifting lever 7 drawn rearwardly until the member 5 is disengaged from the notch 4, when said lifting lever 7 may be readily adjusted longitudinally of said standard 2.

From the foregoing it will be readily seen that I have provided a lifting jack which will be of extremely simple construction and operation as well as highly efficient in use 35 and one in which the parts will be formed in such manner that they may be readily and cheaply manufactured and should any of such parts become worn or broken they may be readily replaced at a small cost.

40 While the preferred embodiment of the invention has been shown and described, it will be understood that minor changes in the details of construction, combination and

arrangement of parts may be made without departing from the spirit and scope of the 45 invention as claimed or sacrificing any of the advantages thereof.

Having thus described the invention what is claimed as new, is:—

1. A device of the class described comprising the combination with a base and a standard projecting upwardly therefrom and having notches in one longitudinal edge, of a lifting lever extending through said standard, a member pivoted to said lifting lever and adapted for engagement with one of said notches, means carried by said lifting lever and connected with said member to clamp the same upon said standard and thereby prevent movement of said lifting lever longitudinally of said standard, a locking rod carried by said standard, and a locking bar carried by said lifting lever for engagement with said locking rod to lock the lifting lever against pivotal movement 55 in one direction.

2. A device of the class described comprising a standard having notches formed in one face, a base for said standard, said standard being formed of spaced parallel 70 members, a lifting lever extended between said parallel members, a supporting member carried by said lifting lever for engagement with the notches of the standard to secure said lifting lever in adjusted position longitudinally of said standard, means for clamping said supporting member in engagement with said standard, and means for automatically locking the lifting lever against pivotal movement in one direction.

In testimony whereof I affix my signature in presence of two witnesses.

CHRISTIAN S. LEHMAN.
